CLAIM

The ornamental design for a ring with the interchangeable cover, as shown and described.

DESCRIPTION

FIG. 1 is a perspective view of the ring with interchangeable cover, showing our new design;

FIG. 2 is a front view of the design illustrated in FIG. 1; FIG. 3 is a rear view of the design illustrated in FIG. 1; FIG. 4 is a right side view of the design illustrated in FIG. 1;

FIG. 5 is a right side view of the design illustrated in FIG. 1;

FIG. 6 is a top view of the design illustrated in FIG. 1; FIG. 7 is a bottom view of the design illustrated in FIG. 1; FIG. 8 is a perspective view of the ring with the interchangeable cover partially removed; and,

FIG. 9 is a perspective view of the ring with the interchangeable cover fully removed.

The broken lines in the drawings are for the purpose of illustrating unclaimed portions of the ring with interchangeable cover and form no part of the claimed design.

1 Claim, 7 Drawing Sheets
